UNITED STATES PATENT OFFICE.

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

RULING APPARATUS.

1,404,738.

Specification of Letters Patent. Patented Jan. 31, 1922.

Application filed September 22, 1919. Serial No. 325,369.

To all whom it may concern:

Be it known that I, ALBERT BROADMEYER, a citizen of the United States, residing at Harrisburg, in the county of Dauphin and 5 State of Pennsylvania, have invented certain new and useful Improvements in Ruling Apparatus, of which the following is a specification.

As is well understood to those skilled in 10 the art in that type of ruling mechanism in which pens are employed, means are provided for lifting the pens from the paper or work at intervals, this lifting action depending upon the character of the ruling 15 to be produced. It often occurs that the lines ruled are to be broken for very small spaces, and difficulty has heretofore been experienced in securing the necessary quick elevation and return of the pens.

20 The object of the present invention is to provide means whereby this movement can be exceedingly quick, notwithstanding the slow action of the main operating or driving parts, and the time of action can 25 be easily, quickly and accurately varied so as to insure high grade results.

In the accompanying drawings,

Figure 1 is a side elevation of an embodiment of the invention, which may constitute 30 a modification or portion of the ruling apparatus disclosed in my co-pending application Serial No. 325,368, filed September 22, 1919,

Figure 2 is a plan view of a portion of the 35 same,

Figure 3 is an end elevation thereof,

Figure 4 is a detail view of a portion of the operating means shown in Figure 3, but in a different position,

40 Figure 5 is a detail sectional view on the line 5—5 of Figure 2,

Figure 6 is a detail sectional view on the line 6—6 of Figure 1,

45 Figure 7 is a detail sectional view of the supporting latch or cam.

Similar reference numerals designate corresponding parts in all the figures of the drawings.

As disclosed in the aforesaid application 50 the work or paper to be ruled is conveyed through the machine by means of an endless carrier belt 8, upon which are located endless cords 9 shown in cross section in Figure 3. This conveyer moves the paper

beneath a series of ruling pens 10 of a 55 well known type. The pens are carried by a holder 11 that is secured to a supporting beam 12 pivotally mounted at its ends. Fixed to the beam for the purpose of swinging the same and thus elevating and depressing the pens, is an actuated member in the form of a crank arm 13. The arm, as shown in Figure 5, is pivotally mounted at 14 to the beam and is held in desired relation with respect thereto by set screws 60 15 threaded through the arm on opposite sides of the pivot and bearing against abutments 16 that are fixed with relation to the beam. A spring 17, connected to the arm 13, serves to swing said arm downwardly, to carry the pens 10 into engagement with the work.

A base plate 18 is mounted on the frame bar 19 of the machine, and is provided with a guideway 20 in which is slidably 75 mounted a bracket 21. This bracket is adjusted by means of a screw 22 threaded therethrough, and having a bearing 23 in the inner end of the base plate. Two rocker arms 24 and 25 are pivotally mounted side 80 by side in the bracket, as shown at 26. The rocker arm 24 has a bearing plate 27 thereon which is engaged by the lower end of a screw 28 threaded through the free end of the crank arm 13 and normally held 85 against accidental movement by a lock nut 29. The downward movement of the arm 24 is determined by a screw 30 threaded through an offset ear 31 carried by said arm 24, the screw being adapted to engage 90 the base plate 18, as shown in Figure 1.

The other arm 25 is provided with a barrel 32, in which is slidably mounted a stem 33 actuated by an adjusting screw 34 shown in Figure 6. The inner end of this 95 stem had a head 35 provided with a finger 36. The free end of the crank arm 13 carries an upstanding bracket 37 in which is pivoted a latch or dog 38 having an outstanding beveled plate 39. The finger 36 is 100 adapted to engage the under side of the plate 39 when the rocker arm 25 is raised, and the latch is so constructed that it will, under upward pressure, remain in horizontal position, as will be evident by reference to 105 Figure 3. The upward swing of the finger will, however, cause it to pass the latch after the crank arm has been raised a prede-

termined distance, releasing the arm and permitting it to return in advance of the return of the arm 25, and when said arm returns the finger 36 will displace the latch or dog, as illustrated in Figure 4, and return to its position beneath the same. To insure the proper action of the dog or latch plate 39, a coiled spring 40 bears thereupon, said spring being coiled around a guide standard 41 passing through a slot in the latch.

For the purpose of effecting the movements of the rocker arms 24 and 25, a driving shaft 42 is located transversely of the rocker arms, and is operated from any suitable source of power. Mounted on the shaft 42 is a double cam disc 43 having peripheral grooves 44 in which may be placed cam plates, as 45. These cam plates can be held at different points in the grooves by suitable set screws 46. The free ends of the rocker arms are disposed over the cam discs and are provided with rollers 47 that ride on the peripheries of the discs and on the edges of the cam plate 45 secured therein.

In order to govern the downward movement of the rocker arm 24 to prevent vibration and jar to the pens, when moving downward upon the paper, said arm is permanently fixed to the pivot 26, so that the pivot has a rotary motion in the bracket 31. Said bracket is provided with an outstanding integral split collar 48 that may be made to grip one end of the pivot 26 through the medium of a contracting screw 49 connecting the ends of the split collar 48. The other arm 25 is loose upon the pivot 26. In order to hold either or both rocker arms 24 and 25 out of action by the cam, latches 50 are pivotally mounted on the base plate 18, the pivots for said latches being designated 51, these latches having bearing portions 52 and handles 53. The bearing portion 52 of one of the latches is adapted to swing to a position beneath the screw 30 of the arm 24, while the corresponding portion of the other latch is adapted to be placed beneath a positioning screw 54 carried by the arm 25. When so positioned beneath the screws the rocker arms are held sufficiently high to prevent the rollers 47 engaging the cam plates 45. Springs 55, surrounding the pivots 51 of the latches, serve to automatically swing said latches to positions out of the paths of the screws 30 and 54, their outward movement being limited by stop pins 56. The arms 24 and 25 preferably have finger rings 57 and 58 by which they can be conveniently lifted.

Briefly described, the operation of the mechanism is as follows. The paper, as already described, is conveyed beneath the pens 10, and where it is desired to make relatively extended breaks in the lines, a cam plate 45 is placed so as to elevate the

arm 24. When so elevated, this motion is transmitted to the crank arm 13, thereby swinging the pen beam 12 and raising the pens from the paper. They are thus held elevated by the cam plate, and when said cam plate has passed the roller, the rocker arm 24 returns and permits the return of the pens. When an exceedingly short space is to be jumped, a cam plate is placed so as to operate the arm 25, and when said arm is elevated, as already explained, the finger 36 will engage the dog and move it upwardly with a corresponding movement of the crank arm and the pens until the finger passes said dog, whereupon the crank arm 80 and the pens will quickly return. The amount of this movement can be varied by adjusting the finger inwardly or outwardly to engage more or less beneath the dog, and consequently the quickness of the action 85 may be made entirely independent of the initial character of the actuating cam employed.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In ruling apparatus, means for moving a ruling instrumentality to and from its work, comprising angularly disposed swinging arms, the pivot axis of one of the arms 105 being disposed transversely to the pivot axis of the other arm, means for periodically operating one of the arms, and a trip connection between the arms for transmitting a predetermined movement by the periodically actuated arm of the other arm and effecting the release of said other arm to permit its return movement prior to the return movement of the periodically operated arm.

2. In ruling apparatus, a movable marker carrying device, a rotatable cam adjacent to one end thereof and having its axis of movement transverse to said end of the marker carrying device, an actuated arm connected 120 to the marker carrying device, a rocker arm operated by the cam and disposed transversely to the actuating arm, and a trip connection between the angularly disposed arms that effects the movement in one direction of the actuated arm by the rocker arm and releases the actuated arm to permit its return independently of the actuating arm.

3. In ruling apparatus, a pivotally 130

- mounted marker carrying device, a rotatable cam adjacent to one end thereof and having its axis of movement transverse to the pivot axis of the marker carrying device, a crank arm connected to the marker carrying device, a rocker arm operated by the cam and disposed transversely to the crank arm, and a trip connection between the angularly disposed arms that effects the movement in one direction of the crank arm by the rocker arm and releases the crank arm to permit its return independently of the actuating arm. 10
4. In ruling apparatus, means for moving a ruling instrumentality including an actuated member, a rocker arm, a cam for periodically operating the rocker arm, and a trip connection between the actuated member and a portion of the rocker arm located between the pivot axis of the arm and the portion operated on by the cam, said trip connection effecting an operation of the actuated member and its release from the rocker arm. 15
- 25 5. In ruling apparatus, means for moving a ruling instrumentality, including an actuated member, a rocker arm pivotally mounted at one end, a cam that operates on the other end of the rocker arm, and a trip connection between the actuated member and an intermediate portion of the rocker arm located between the pivot axis of the arm and the portion operated on by the cam, said trip connection effecting an operation of the actuated member and its release from the rocker arm. 30
- 35 6. In ruling apparatus, means for moving a ruling instrumentality, including a movable actuated member, a movable actuating member therefor, a latch pivotally mounted on one member, a stop for limiting the movement of the latch in one direction, and a finger carried by the other member and adapted to detachably engage and disengage the latch on the movement of the actuating member. 40
- 45 7. In ruling apparatus, means for moving a ruling instrumentality, including a movable actuated member, an overhanging latch pivotally mounted on the actuated member and abutting thereagainst to limit its swinging movement, a movable actuating member and a portion moving therewith and adapted to detachably engage and disengage the latch on the movement of the actuating member. 50
- 55 8. In ruling apparatus, means for moving a ruling instrumentality, to and from its work, comprising a swinging actuated arm, a swinging actuating arm, a latch pivoted on the actuated arm, a finger mounted on the actuating arm and detachably engaging the latch to move the actuated arm in one direction and release the same to permit its return independently of the actuat- 60
- 65 ing arm, and means moved by the actuating arm for moving a marking device. 70
9. In ruling apparatus, the combination with a swinging pen supporting beam, of a crank arm carried thereby, a latch pivoted on the crank arm, a rocker arm, a cam for moving the rocker arm, and a finger carried by the rocker arm and detachably engaging with the latch to move the same and the crank arm. 75
10. In ruling apparatus, means for moving a ruling instrumentality, including a movable actuated member, a movable actuating member, a latch movably mounted on one member, and a finger adjustably mounted on the other member and movable longitudinally and laterally of said other member, said finger engaging and disengaging the latch to effect a predetermined movement of the actuated member. 80
11. In ruling apparatus, means for moving a ruling instrumentality, including a movable actuated member, a movable actuating member, a latch movably mounted on one member, and a finger slidably and rotatably mounted on the other member and engaging and disengaging the latch to effect a predetermined movement of the actuated member. 85
12. In ruling apparatus, means for moving a ruling instrumentality, including a movable actuated member, a movable actuating member, a latch movably mounted on one member, and a finger slidably mounted on the other member and engaging and disengaging with the latch, and means for slidably adjusting the finger on said other member and holding it in different adjusted positions. 90
13. In ruling apparatus, means for moving a ruling instrumentality, including a movable actuated member, a movable actuating member, a latch movably mounted on one member, and a finger slidably mounted on the member and engaging and disengaging with the latch, and an adjusting screw connection between the said other member and latch. 95
14. In ruling apparatus, means for moving a ruling instrumentality, including a movable actuated member, a movable actuating member, a latch movably mounted on one member, and a finger rotatably mounted on the other member and disposed eccentrically to its axis of rotation, said finger engaging and disengaging the latch to effect a predetermined movement of the actuated member. 110
15. In ruling apparatus, means for moving a ruling instrumentality, including a movable actuated member, a movable actuating member, a latch movably mounted on one member, a stem slidably and rotatably mounted on the other member and having an eccentric finger that engages and disen- 115
- 120
- 125
- 130

gages the latch, and means for holding the stem in different positions.

16. In ruling apparatus, the combination with a pivotally mounted pen supporting beam, of a crank arm connected thereto, a latch pivotally mounted on the crank arm, a rocker arm, a finger slidably mounted on the rocker arm and engaging with the latch upon the movement of the rocker arm in one direction, a screw adjustment for moving the finger toward and from the latch, and a cam that engages the rocker arm to operate the same.

17. In ruling apparatus, the combination with a pen support moving member, of a plurality of actuating arms, an adjustable bearing between the member and one of the arms, and an adjustable trip mechanism between the member and the other arm.

18. In ruling apparatus, the combination with a pen support moving member, of a plurality of actuating arms, an adjustable bearing between the member and one of the

arms, a latch movably mounted on the member, and a finger adjustably mounted on the other arm and engaging and disengaging the latch.

19. In ruling apparatus, the combination with a pen support, of a crank arm for moving the same, cam mechanism located at one end of the pen support and having its axis of rotation transverse to said end of the pen support, a pair of rocker arms mounted transversely of the crank arm and operated by the cam mechanism, an adjustable bearing between the crank arm and one of the rocker arms, a latch pivoted on the crank arm, and a finger adjustably mounted on the other rocker arm and engaging and disengaging the latch.

In testimony whereof, I affix my signature in the presence of two witnesses.

ALBERT BROADMEYER.
